Specification for Design.

Patented Feb. 4, 1913.

Application filed October 28, 1912. Serial No. 728,292. Term of patent 14 years.

To all whom it may concern:

Be it known that I, ISAIAH E. HINDMAN, a resident of Crafton, in the county of Allegheny and State of Pennsylvania, have invented a new, original, and ornamental Design for Lifting-Jack Frames, of which the following is a specification, reference being had to the accompanying drawings, forming part thereof, in which—

Figures 1 and 2 are perspective views showing the design from opposite corners thereof.

I claim:

The ornamental design for a lifting jack frame, as shown.

In testimony whereof, I have hereunto set my hand.

ISAIAH E. HINDMAN.
